SEWING MACHINE COVER PLATE

Andrew B. Clayton, Union, N. J., assignor to The Singer Manufacturing Company, Elizabeth, N. J., a corporation of New Jersey

Application September 12, 1941, Serial No. 410,521

8 Claims. (Cl. 112—258)

The invention relates to new and useful improvements in cover-plates for a sewing machine.

An object of the invention is to provide a sewing machine frame with one or more cover-plates equipped with substantially unitary latching mechanisms of simple design which facilitate assembly of the machine.

A more specific object of the present invention is to provide a pair of cover-plates having a common latching mechanism for a work-supporting arm of a sewing machine.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

Fig. 1 is an end elevation of the machine.

Fig. 2 is a perspective view of the work-supporting arm end-section showing both cover-plates in open positions.

Fig. 3 is a top plan view of the work-supporting arm end-section, the cover-plate being shown as closed in full lines and as open in broken lines.

Fig. 4 is a right side view of work-supporting arm disclosed in Fig. 2 and showing one of the cover-plates as closed in full lines and as open in broken lines.

Fig. 5 is a front end view of the work-supporting arm of Fig. 2 illustrating both cover-plates in open positions.

Fig. 6 is a vertical section taken substantially along line 6—6 of Fig. 1, and showing the cover-plates as closed in full lines and as open in broken lines.

Fig. 7 is a horizontal section taken substantially along line 7—7 of Fig. 5 and showing portions of the cover-plates as open in broken lines, and the latching mechanism and cover-plate mounting means as closed in full lines.

Fig. 8 is a portion of a vertical section taken substantially along line 8—8 of Fig. 4 and showing the latching mechanism in closed positions.

Fig. 9 is a vertical section taken along line 9—9 of Fig. 7.

The present invention is herein illustrated as employed on a feed-off-the-arm sewing machine. The machine frame includes the usual gooseneck 10 which terminates at its free end in the hollow head 11 carrying the reciprocating needle-bar 12 and the presser-bar 13 fitted, respectively, with needles 14 and presser-foot 15. Both the needle-

bar 12 and the presser-bar 13 are actuated by the usual mechanisms, such as illustrated in my Patent No. 1,996,040, dated Mar. 26, 1935.

The gooseneck 10 is rigidly mounted upon a U-shaped bed 16 only a part of which is herein shown, and rearwardly extending from a portion of this bed is a hollow horizontal work-supporting arm 17 terminating at its free end below the head 11.

10 Mounted in the free end of the arm 17 are the usual feeding and looper mechanisms as represented, respectively, by the feed-dogs 18 and the loopers 19. The feeding and looper actuating mechanisms are driven from the usual needle-bar actuating shaft 20 by means of the conventional clip-belt (not shown) housed within the belt-casing 21 exteriorly of the sewing machine frame proper.

15 The free end of the hollow work-supporting arm 17 is enclosed by means of an end-wall 22, and mounted upon the top portion of the arm is a conventional throat-plate 23. Substantially oppositely disposed openings, defined, respectively, by the cut-away side walls 24 and 25, are 20 provided in the arm 17 for clearance or inspection openings through which the loopers 19 may be properly threaded. These openings 24 and 25 are closed during the normal sewing operations by means of cover-plates 26 and 27, respectively. 25 The end-wall 22 of the arm 17 is provided with a pair of horizontally disposed grooves 28, each designed to receive a portion of a cover-plate so that the latter elements may be properly recessed within the openings, as illustrated in Figs. 3 and 6.

30 Horizontally disposed within the end-wall 22 is a cylindrical aperture 29 within which latching mechanism is slidingly mounted. The cover-plates 26 and 27 are mounted upon the outer ends 35 of this mechanism. This latching mechanism comprises two coaxial cylindrical units or plungers 30 and 31 which are urged toward each other within the aperture 29 by means of a coil-spring 32. Each of the units 30 and 31 is provided with 40 a central bore 33 extending lengthwise thereof, and an end of the spring 32 is anchored within each of said bores 33 by means of a pin 34 mounted crosswise within each cylindrical unit.

45 Secured to the face of the end wall 22 by means of a screw 35 is an arm 36 which is associated with the units 30 and 31 through the medium of two guide and stop elements 37 and 38, formed on the respective end-portions of the arm 36.

50 The guide and stop element 37 is received by a slot 39 formed in the unit 31 and, as the element

31 is stationary, it functions, as best illustrated in Fig. 8, to keep the unit 31 from turning about its longitudinal axis and permits it to slide lengthwise of itself. The outward movement of the unit 31 is arrested whenever the stop-element 37 engages the end-wall 40 of the slot 39.

The hinge-piece 41 is pivotally secured within the slot 39 by means of a pin 42 mounted crosswise within the unit 31. Formed on the outer end of the hinge-piece 41 is a rivet portion 43 which secures the cover-plate 27 rigidly to the hinge-piece 41. It may be understood therefore, from the above description, and by particular reference to Fig. 7, that the cover-plate 27 may be pulled outwardly until the stop 37 engages the end-wall 40, at which point the cover-plate may be swung about the vertically disposed pivot-pin 42. The hinge-piece 41 is arcuate in shape along the edge 44 thereof to permit the piece to be properly pivoted. As best illustrated in Fig. 7, the pointed portion 45 of the hinge-piece and the lip 46 of the cover-plate 27 function as stops which engage diametrically opposite points of the side walls of the aperture 29 to thereby lock the cover-plate 27 in open position.

To lessen the cost of manufacture, a slot corresponding to slot 39 of the unit 31 was not provided in the other unit 30. In lieu of such a slot, shoulders 47 are formed on the unit 30 and, as shown by Fig. 9, these shoulders 47 will engage the guide 38 and thereby permit the unit to turn only slightly about its longitudinal axis. A vertically disposed slot 48, however, is provided in the unit 30 for the purpose of receiving the guide 38 and thereby permitting the unit to be turned about its longitudinal axis. However, as illustrated by the broken lines of Fig. 7, the unit must first be shifted outwardly for the slot 48 to engage the guide 38. The outward movement of the unit 30 is arrested whenever the stop element 38 engages the end-wall 49 of the slot.

The outer end of the unit 30 is provided with a rivet portion 51 which rigidly secures the cover-plate 26 thereto. From the above description it will be understood that the cover-plate 26 may be shifted outwardly and then shifted downwardly about the longitudinal axis of the unit 30. The stop 38 will, while engaged by the slot 48, lock the cover-plate 26 in its outward position.

The cover-plates 26 and 27 are each provided with a spring-arm 52 secured to the inner face thereof for the purpose of engaging the respective side-walls 24 and 25 of the arm 17 to thereby cooperate with the coil-spring 32 in yieldingly retaining the cover-plates in closed positions. Slots 53 are formed in the cover-plates 26 and 27 to provide openings through which lint and other foreign matter may escape from the hollow arm 17. As best illustrated in Fig. 3, the lips 46, which are formed on the end-portions of the cover-plates 26 and 27, extend forwardly past the face of the end-wall 22 and thereby function as finger-pieces, by means of which an operator may more readily grasp said plates for manipulating the same.

From the above description it will be obvious that either of the two cover-plates 26 or 27, with its respective plunger unit 30 or 31, could be omitted from the present machine without impairing the function or operation of the remaining unit. The free end of the coil-spring 32 would need only be secured to the machine arm 17 and the remaining cover-plate would function properly.

Having thus set forth the nature of the invention what I claim herein is:

1. In a sewing machine, the combination of a hollow frame having an inspection opening therein and a cylindrical aperture adjacent said inspection opening, a cylindrically shaped plunger shiftably mounted within said aperture, said plunger being provided with a longitudinally disposed central bore and a slot formed in the outer surface of the plunger and disposed lengthwise thereof, a coil spring having one end secured within said bore and the other end secured without said plunger so as to force the plunger into said aperture, a guide and stop element carried by said frame, said element engaging said slot for the purpose of preventing rotative movement and for limiting the shifting movements of said plunger, a hinge-piece pivotally mounted upon the outer end of said plunger, and a cover-plate 10 fixedly secured to said hinge-piece and adapted to normally cover said inspection opening.

2. In a sewing machine, the combination of a hollow frame having an inspection opening therein and a cylindrical aperture adjacent said inspection opening, a cylindrically shaped plunger shiftably mounted within said aperture, said plunger being provided with a longitudinally disposed central bore and a slot formed in the outer surface of the plunger and disposed transversely 15 of its longitudinal axis, a coil spring having one end secured within said bore and the other end secured without said plunger so as to force the plunger into said aperture, a guide and stop element carried by said frame, said element engaging said slot for the purpose of guiding the rotative movements of said plunger and to lock the plunger in a predetermined position, shoulders formed on the outer surface of said plunger 20 for the purpose of engaging said guide and stop element so as to limit certain rotative movements of said plunger, and a cover-plate rigidly secured upon the outer end of said plunger and normally disposed over said inspection opening.

3. A hollow sewing machine frame having opposed inspection openings therein and formed with a transverse aperture adjacent said inspection openings, a pair of spring connected plungers disposed end-to-end in said aperture, and cover-plates for said inspection openings mounted each on the outer end portion of a respective 25 one of said plungers.

4. In a sewing machine, the combination of a work-supporting arm having a pair of substantially oppositely opposed openings therein, latching mechanism carried by said arm and including two separable coaxial units, spring means to urge said units towards each other, said units being adapted to be shifted relative to each other lengthwise of their common axis in opposition to said spring means, means to prevent said separable units from rotating about their common axis, stop elements secured to said arm and associated with said units for limiting the lengthwise shifting movements thereof, means to lock said units in predetermined positions, and a pair of cover-plates each mounted on an outer end of one of said separable units, each cover-plate being normally disposed over one of said arm openings.

5. In a sewing machine, the combination of a work-supporting arm having a pair of substantially oppositely disposed inspection openings therein and formed with a transverse aperture adjacent said inspection openings, a pair of spring connected plungers disposed end-to-end

in said aperture and being adapted to be shifted lengthwise of and relative to each other, stop and guiding elements secured to said arm and associated with said plungers for limiting the lengthwise shifting movements thereof, means to lock said plungers in predetermined positions, and a pair of cover-plates each mounted on an outer end of one of said plungers, each cover-plate being normally recessed within one of said inspection openings.

6. A hollow sewing machine work-supporting arm having opposed inspection openings adjacent its free end and formed with a transverse aperture adjacent said inspection openings, a pair of cylindrically shaped plungers disposed end-to-end in said aperture and being adapted to be shifted lengthwise of and relative to each other, each of said plungers having a longitudinally disposed central bore, a spring element one end of which is secured within a respective plunger bore, a pair of stop and guide elements secured to said arm and engaging said plungers for the purpose of limiting and guiding the movements thereof, and a pair of cover-plates each mounted on an outer end of one of said plungers, each cover-plate being normally recessed within one of said inspection openings.

7. A hollow sewing machine frame having an inspection opening therein and formed with a transverse cylindrical aperture adjacent said inspection opening, a cylindrically shaped plunger shiftably mounted within said aperture and having a retracted and an extended position, a spring mounted within said aperture and engaging said

plunger so as to urge the same into its retracted position, said plunger having a slot formed therein, a guide element carried by said frame and engaging said slot for the purpose of limiting the movement of said plunger, a cover-plate for said inspection opening mounted upon said plunger and normally disposed substantially at right angles to the longitudinal axis of said plunger, and latching means operable in response to a turning movement of said cover-plate for locking said plunger in its extended position.

8. A hollow sewing machine frame having an inspection opening therein and formed with a transverse cylindrical aperture adjacent said inspection opening, a cylindrically shaped plunger shiftably mounted within said aperture and having a retracted and an extended position, a spring mounted within said aperture and engaging said plunger so as to urge the same into its retracted position, said plunger having a longitudinal slot formed therein, a guide element carried by said frame and engaging said slot for the purpose of limiting the movement of said plunger, a cover-plate for said inspection opening hingedly mounted upon said plunger and normally disposed substantially at right angles to the longitudinal axis of said plunger, a latching element carried by said cover-plate for engaging said frame in response to a pivotal movement of said cover-plate for the purpose of locking said plunger in its extended position.

ANDREW B. CLAYTON.
